UNITED STATES PATENT OFFICE.

ROBERT HOE, OF HYDE PARK-ON-HUDSON, NEW YORK.

IRONING MACHINE.

Application filed August 27, 1921, Serial No. 496,045. Renewed August 25, 1927.

This invention relates to ironing machines, and more particularly to machines of the type having a polished rotating cylinder and oppositely rotating covered feed rolls resiliently held in contact therewith. Hitherto no simple and effective means have been provided for separating the feed rolls from the cylinder without disengaging the driving mechanism. According to this invention the feed rolls and the cylinder have a common drive through a single train of gears, with means for separating the feed rolls simultaneously from the cylinder without disengaging any of said gears. The mechanism whereby such separation is effected may be actuated by a simple pedal movement of the attendant from any point along the length of the machine. The return of the feed rolls is likewise effected, and without disengaging any portion of the driving mechanism. Such machines are preferably belt driven by individual electric motors attached to the machine frame; and I have devised a novel means for maintaining proper belt tension.

In carrying out the above mentioned features of the invention, I have produced a machine consisting of a relatively small number of parts, in the manufacture of which the necessary machining operations are reduced to a minimum, which is easy to assemble, simple to operate and of rugged construction, insuring economy of manufacture and of maintenance, durability and effective service. With these and other objects in view, I have devised the apparatus embodying my invention, as described in the following specification and illustrated in the accompanying drawings, wherein

Figure 1 is a side elevation, and

Figure 2 is an end elevation.

Referring to the drawing, 1 represents the frame of the machine, comprising a pair of end frame members 2 and 3 joined together by longitudinal bracing 4 and carrying upper bearing members 5 and 6 respectively. Each of frame members 2 and 3 has a horizontal transverse flange 7 at its top, while each of members 5 and 6 has a corresponding flange 8 at its bottom, the respective members being bolted together through flanges 7 and 8. A pair of horizontal mutually aligned bearings 9 and 10 are provided between members 2 and 5 and between members 3 and 6 respectively, flanges 7 and 8 being centrally interrupted and extending on either side as

in the case of ordinary split bearings. Rotatably mounted in bearings 9 and 10 is main shaft 11, to which between said bearings is keyed or otherwise securely fixed main cylinder 12 having its outer surface polished. 60

In each of bearing members 5 and 6 are three radial guideways 13, 14 and 15, each of said guideways in either bearing member being parallel to and extending in the same direction from shaft 11 as the corresponding guideway in the opposite bearing member. Travelling in each pair of guideways 13, 14 and 15 is a pair of bearing blocks 16, 17 and 18 respectively, having bearings 19, 20 and 21 respectively. Each 70 bearing block is normally held at the inner end of its respective guideway by a spring 22, the tension of which is regulated by an adjusting screw 23 carried in a threaded member 24, the latter members being secured to upper bearing members 5 and 6 over the outer ends of guideways 13, 14 and 15 respectively. Rotatably mounted in each pair of bearings 19, 20 and 21 respectively, are longitudinal shafts 25, 26 and 27, and keyed 80 or otherwise securely fixed to said respective shafts between the respective pairs of bearings are felt or fabric covered feed rolls 28, 29 and 30. Guideways 13, 14 and 15 extend inwardly a sufficient distance to permit rolls 85 28, 29 and 30 respectively to bear upon cylinder 12 under the pressure of springs 22.

Horizontal feed table 31 is supported on upper bearing members 5 and 6 by brackets 32 and 33 integral with or secured to the 90 respective bearing members 5 and 6, and is disposed upon one side of the machine at such a level as to feed the goods between cylinder 12 and the first roll 28. A longitudinal shaft 34 below the upper surface 95 of table 31 is carried in aligned bearings 35 and 36 formed in brackets 32 and 33 respectively; and moistening roller 37 is keyed or otherwise securely fixed to shaft 34 between bearings 35 and 36. The periphery of roller 100 37 is almost tangent to, and extends slightly above the upper surface of table 31, the table being cut away as at 38 to accommodate roller 37. A trough 39, supported at either end by brackets 32 and 33 respectively, is disposed beneath moistening roller 37, the latter dipping into the water contained in trough 39. Resting upon and parallel to moistening roller 37 is roller 40, 105 keyed or otherwise securely fixed to longi- 110

tudinal shaft 41 between bearings 42 and 43 for the latter, said bearings being carried by brackets 32 and 33 respectively. Bearings 42 and 43 are preferably open at the top to facilitate removal of shaft 41 and roller 40, and are sufficiently deep to permit roller 40 to bear on moistening roller 37, being intended to take only longitudinal and lateral thrust.

- 10 The machine is driven from a pulley 44 keyed upon or otherwise securely fixed to a transverse shaft 45 carried in a pair of aligned bearings 46 bracketed as at 47 to end frame member 3. Between bearings 46
 15 shaft 45 carries a worm 48, either integrally or securely fixed thereto; and mounted upon stub shaft 49 carried in bearing 50 on end frame member 3, and meshing with worm 48, is worm wheel 51. Spur tooth pinion 52,
 20 also mounted on shaft 49 is rigidly fixed to and is driven by worm wheel 51. Keyed to or otherwise securely fixed upon main shaft 11, and meshing with and driven by pinion 52, is gear wheel 53. In the plane of gear
 25 wheel 53, and keyed upon or otherwise securely fixed to each of shafts 25, 26 and 27 respectively, are gear wheels 54, 55 and 56. Between gears 54 and 55, and meshing with both, is gear wheel 57, mounted on stub
 30 shaft 58 carried in bearing 59 in upper bearing member 6. Likewise between gears 55 and 56 and meshing with both, is gear wheel 60 mounted on stub shaft 61 carried in bearing 62 in upper bearing member 6.
 35 Gear wheel 57 is centered close to and slightly outside of the line joining the centers of gears 54 and 55 when the rolls driven by said respective gears are in innermost position; that is, in contact
 40 with main cylinder 12. Gear wheel 60 is similarly centered with respect to gears 55 and 56. Meshing with both of gears 53 and 57, and driving the latter from the former, is gear wheel 63, mounted on stub shaft 64
 45 carried in bearing 65 on end frame member 3. Moistening roller 37 is driven by gear wheel 66 keyed or otherwise rigidly secured to shaft 34 and meshing with and driven by gear wheel 67, the latter being
 50 mounted on stub shaft 68 carried in bearing 69 on bracket 33 and meshing with and driven by gear wheel 53. Keyed upon or otherwise rigidly secured to shafts 34 and 41 respectively are pulleys 70 and 71, the latter being driven from the former by a
 55 belt 72.

Power is supplied by a motor 73, to the rotor 74 of which is directly connected pulley 75. Belt 76 runs between pulleys 75 and 44, and drives the latter from the former. Pulleys 75 and 44 are stepped, and an ordinary belt shifter 77, sliding in guides 78 secured to end frame 3, and actuated by control lever 79 pivoted at 80 to end frame 3, regulates the speed. Motor 73 is hinged or piv-

otally mounted on pin 81 in brackets 82, the latter being secured to end frame 3. A pair of bored lugs 83 secured to the base of motor 73 afford a bearing for the motor on pin 81. The latter is positioned, not directly under the center of gravity of motor 73, but is horizontally spaced from the center of gravity, and it is preferably parallel to the axis of the motor. It will thus be seen that pin 81 constitutes only a partial support for motor 73, the remaining weight of which is carried by belt 76, which is thus made a partial support. The weight thus carried by belt 76 maintains the latter in proper tension. A pair of stop lugs 84 and 85 are bracketed to motor 73 and are provided with adjusting screws 86 and 87 respectively, which by contacting with plate 88 on end frame 3 limit the rotation of motor 73 about pin 81 and prevent the motor from falling in case of breakage of belt 76. The latter is chosen of such length as to maintain the motor in substantially horizontal position, while screws 86 and 87 are adjusted to permit only a slight freedom of movement of motor 73 from its belt supported position.

For lifting rolls 28, 29 and 30, cam rollers 89, 90 and 91 are respectively mounted on bearing blocks 16, 17 and 18. Cams 92 pivotedly mounted as at 93 on end frames 2 and 3, respectively, each have cam surfaces 94, 95 and 96 adapted respectively to engage rollers 89, 90 and 91 when cams 92 are rotated in the proper direction about pivots 93, thus forcing bearing blocks 16, 17 and 18 to move outwardly in guideways 13, 14 and 15, respectively, and raising rolls 28, 29 and 30 out of contact with main cylinder 12. As cams 92 are returned to normal position, rolls 28, 29 and 30 move inwardly until they bear on main cylinder 12, whereupon cam surfaces 94, 95 and 96 will disengage rollers 89, 90 and 91 respectively. Cams 92 are each actuated by a rod 97, pivoted thereto at 98. It will be noted that the feed roll lifting mechanism here described is in duplicate, similar parts being provided at either end of the machine, and the lifting stress is carried by the frame independently of the main roll bearings.

The operation of cams 92 may be effected at any point in the length of the machine by means of an elongated pedal 99 disposed on the feed side of the machine beneath table 31 and secured at either end to levers 100 and 101 respectively, the latter being pivoted at their opposite ends 102 and 103 respectively to cross bracing 4, and intermediately pivoted to the lower ends of cam actuating rods 97 as at 104 and 105 respectively.

Compression springs 106 around rods 97 and maintained between collars 107 on the respective shafts and brackets 108 on frame 1, resiliently hold cams 92 in disengaged

position, that is, so that feed rolls 28, 29 and 30 contact with main cylinder 12. Pedal 99 is thus normally held in raised position.

The pedal 99 is pivoted at each end at 5 115 to tripping bar 116. 117 is a latch lever having a weight 118 and pivoted at 119 on the frame, latch lever 117 passing between lugs 120, 121, on lever 100. When lever 100 is pushed down by pedal 99, the end of the 10 lever 117 engages in notch 122 of lug 120 to hold lever 100 down and the rolls lifted. It is tripped by the bar 116, actuated by the operator's foot striking lever 117 and pushing it to the right in Figure 2, lifting 15 weight 118 and allowing springs 106 to lift levers 100. As will be seen, trip bar 116 slides up and down on the smooth back of lever 117.

Main cylinder 12 is internally heated by 20 a plurality of jets 123 in burner tube 124, which is supported by bracket 125 and is connected to a supply of gas and air. Shaft 11 is hollow to accommodate tube 124, and is discontinuous between the ends of cylinder 25 12 to which it is fixed.

The operation of the device will be apparent from the foregoing description. It should be noted that gear 57 is so centered with respect to gears 54 and 55 that the relative motion between gear 57 and gears 54 30 and 55, when the latter are moved with their respective rolls to engage or disengage the work, is substantially tangential. This fact, taken in view of normal tooth clearance, makes it clear that jamming of the 35 teeth will be avoided. Likewise gear 60 is similarly centered with respect to gears 55 and 56. This arrangement permits gears 54, 55 and 56 to move in or out with respect 40 to gears 57 and 60 for the distance necessary to engage or disengage the work between the cylinder and the feed rolls without disengaging. In such movement, supposing the machine to be at rest, gear 55 would be stationary, and would cause rotation in op-

posite directions, by reason of its translatory movement, of adjacent gears 57 and 60, which in turn would cause opposite rotation of gears 54 and 56. When the machine is in operation, such rotations will be superposed upon the normal motions of the respective gears. 50

The other features of having the motor automatically hold the belt tension, and the latching and tripping mechanism are of decided practical advantage because simple and rugged, so as to be handled by unskilled attendants. 55

A further advantage of this machine shown in Figure 1 is that the ends of the ironing roll are undercut as shown so that the covering on the pressure rolls can wear down without causing the flanges of the rolls to contact and interfere with the pressure. 60

What I claim is:

An ironing machine comprising a cylinder, a feed roll parallel thereto, a pair of feed rolls parallel to and disposed on opposite sides of said first feed roll, movable bearing means for said feed rolls, a guide for 65 each of said bearing means permitting the latter together with the roll supported thereby to move toward and away from said cylinder, means normally holding each of said rolls in contact with said cylinder, bearing 70 means for said cylinder, a driving gear secured to each roll, a driving gear secured to said cylinder, intermediate gears connecting up all of said driving gears, means for driving the chain of gears thus constituted, and means for moving said feed rolls out of contact with said cylinder to disengage the work without moving the intermediate gears or disengaging or jamming 75 said driving means or any of the gears of 80 said chain. 85

Signed at New York in the county of New York and State of New York this 26th day of August, A. D., 1921.

ROBERT HOE.
